US0D1062733S

(12) **United States Design Patent** (10) Patent No.: **US D1,062,733 S**
 Magi et al. (45) Date of Patent: ** Feb. 18, 2025

(54) **ELECTRONIC DEVICE AND AUXILIARY DISPLAY**

(71) Applicants: **Aleksander Magi**, Portland, OR (US); **Mark E. Sprenger**, Tigard, OR (US); **Kimi Jensen**, Beaverton, OR (US); **Emery Frey**, Portland, OR (US)

(72) Inventors: **Aleksander Magi**, Portland, OR (US); **Mark E. Sprenger**, Tigard, OR (US); **Kimi Jensen**, Beaverton, OR (US); **Emery Frey**, Portland, OR (US)

(73) Assignee: **Intel Corporation**, Santa Clara, CA (US)

(**) Term: **15 Years**

(21) Appl. No.: **29/881,408**

(22) Filed: **Dec. 30, 2022**

(51) LOC (15) Cl. **14-02**

(52) U.S. Cl.

USPC **D14/388**

(58) **Field of Classification Search**

USPC D14/391-393, 396, 320, 417, 398; D18/1, 2, 6, 7

CPC G06F 3/021; G06F 3/0216; G06F 3/0219

(57) **CLAIM**

The ornamental design for an "electronic device and auxiliary display" as shown and described.

DESCRIPTION

FIG. 1 is a front perspective view of an electronic device with an auxiliary display coupled on a side of the electronic device; and,

FIG. 2 is a top view of the electronic device and auxiliary display of FIG. 1.

The features shown in broken lines form no part of the claimed design.

1 Claim, 2 Drawing Sheets
